UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

COMBINED STIFFENING AND CLOSING DEVICE FOR BAGS.

Application filed March 14, 1918. Serial No. 222,283.

To all whom it may concern:

Be it known that I, FREDERICK GOERTZ, a citizen of the United States, residing at Newark, in the county of Essex and State of New Jersey, have invented certain new and useful Improvements in Combined Stiffening and Closing Devices for Bags; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in bags; and, the present invention has reference, more particularly, to that class of bags, known in the art as knitting bags.*

The present invention, therefore, has for its principal object to provide a novel knitting bag of the general character hereinafter set forth; and, furthermore, to provide a novel and simply constructed stiffening device comprising a pair of separable closing members, upon which the mouth-portions of the bag are shirred, said members acting as a means for positively closing the mouth of the bag, but at the same time being readily separated for opening the mouth of the bag, and the said members also serving to provide a means for the attachment thereto of the ends of the strap or handle by means of which the bag is carried.

Other objects of the invention not at this time more particularly enumerated will be clearly understood from the following detailed description of the present invention.

With the various objects of the present invention in view, the said invention consists, primarily, in the novel knitting bag and closing device therefor, to be hereinafter more fully set forth; and, the invention consists, furthermore, in the novel arrangements and combinations of the several devices and parts, as well as in the details of the construction of the said parts, all of which will be more fully described in the following specification, and then finally embodied in the clauses of the claims which are appended

to and which form an essential part of the said specification.

The invention is illustrated in the accompanying drawings, in which:—

Figure 1 is a face view of a knitting bag made according to and embodying the principles of the present invention.

Figure 2 is a view of the bag-closing and stiffening device to be employed with the bag, showing the two stiffening members in their locked relation when closing the mouth of the bag, but the bag being omitted from said view.

Figure 3 is a view of the same device, but showing the stiffening members thereof in the act of being separated when it is desired to open the mouth of the bag; and Figure 4 is a transverse vertical section of the device, said section being taken on line 4—4 in Figure 2, looking in the direction of the arrow x.

Figure 5 is a view, partly in plan and partly in horizontal section, of a slightly modified form of closing and stiffening device for a knitting bag.

Similar characters of reference are employed in all of the said above described views, to indicate corresponding parts.

Referring now to the said drawings, the reference-character 1 indicates the body of a knitting bag, and 2 the shirred portions which surround the mouth of the bag.

The combined closing and stiffening, illustrated more particularly in Figures 2, 3 and 4 of the drawings, is indicated in general by the reference-character 3, the said device comprising two rods or bars, as 4 and 5, which may be of metal, or any other suitable material, one of said rods, as 5, being of greater length than the rod 4. At or near its end-portions, the rod or bar 4 has rigidly connected therewith by means of solder 6, or other suitable fastening means, rings 7 and 8, providing suitable receiving members to which are suitably attached the respective end-portions 10, or other fastening members, of a carrying strap or handle 9. Suitably mounted upon the respective end-portions of the rod or bar 5, are ornamental knobs or enlargements, as 11 and 12, or other engaging and retaining means, which,

when the shirred portions 2 of the bag-body have been mounted upon the respective rods or bars, are adapted to be passed through the respective rings, loops, or the like of the 5 rod or bar 4, as will be understood from an inspection of Figure 3 of the drawings, and brought into holding or retaining engagement with the respective rings in the manner illustrated in Figures 1 and 2 of the 10 drawings.

The said rods or bars 4 and 5 are of such thickness and stiffness, that the rods when secured to the mouth of the bag-body, will not bow outwardly, that a rigid stiffening 15 and closing device for the mouth of the bag will be provided, to keep the same closed, and at the same time permit the bag to be safely carried about by means of the strap or handle 9.

20 When it is desired to open the mouth of the bag, all that is necessary is to force the knob or enlargement 11 through the ring or loop 7 to bring the rods or bars into the relative positions illustrated in Figure 3 of the drawings, and then by moving the said 25 rod or bar 5 in the direction of the arrow y, the knob or enlargement 12 is withdrawn from the ring or loop 8, so that the mouth of the bag is brought into its fully opened 30 relation to the body of the bag.

In lieu of the combined stiffening and closing means illustrated in said Figures 1 to 4 inclusive, I may use a modified device of the character represented in Figure 5 35 of the drawings.

This device comprises a rod or bar 13, upon the end-portions of which are suitably mounted suitably shaped knobs or enlargements, as 14 and 15, or other suitable holding or retaining means. Instead of the previously described single rod 5, provided with the rings 7 and 8, a tubular rod or member, as 16 may be employed, upon one end-portion is secured by means of solder 40 17, or other fastening means, a ring or loop 18, to which is attached the one end-portion of the carrying strap or handle 9. Movably disposed within a portion of the said tubular rod or member 16 is a short rod or bar 19 projecting from the open end-portion 20 of said rod or member 16, and having suitably secured upon the said projecting end of the rod or bar 19, by means of solder 21, or otherwise, a ring or loop 22, for attachment thereto of the other end of the carrying-strap or handle 9. Suitably connected with the end-portion 23 of said rod or bar 19, is the end 25 of a coiled spring 24, said spring being disposed within the 45 tubular rod or member 16, and having its other end 26 secured in a fixed portion within said rod or member 16 by means of a pin 27, or other suitable fastening means.

The engaging and retaining relation of 50 these several parts, and the manner of sep-

arating the closed relation of the rods 13 and 16, to open the mouth of the bag, when arranged in the shirred portions of the bag-body, will be fully understood from an inspection of said Figure 5 of the drawings. 70

Of course I am fully aware that changes may be made in the general arrangements and combinations of the several devices and parts, as well as in the details of the construction of the said parts, and that the said 75 combined stiffening and closing device may be otherwise attached to the mouth-portions of the bag-body, and may be used with bags other than knitting bags. Hence, I do not limit my present invention to the exact arrangements and combinations of the several devices and parts as described in the foregoing specification, nor do I confine myself to the exact details of the construction of the said parts as illustrated in the accompanying drawings. 80

I claim:—

1. A combined stiffening and closing device for bags, comprising a pair of closing members for attachment thereto of the 90 mouth-portions of the bag, loop-shaped devices rigidly connected in fixed relation with one of said closing members and extending at right angles therefrom, a carrier-strap or handle secured at its ends to said loop-shaped devices, and retaining knobs connected with the other closing member adapted to enter said loop-shaped devices for separable retaining engagement therewith. 95

2. A combined stiffening and closing device for bags, comprising a pair of closing members for attachment thereto of the mouth-portions of the bag, one of said members comprising a single rod provided at its ends with enlargements or knobs, and the other member comprising a tubular rod, and a bar movably disposed within said tubular rod with an end of said bar projecting from one end of said tubular rod, a loop-shaped device rigidly connected with the projecting end of said bar and extending at a right angle therefrom, a second loop-shaped device rigidly connected with the opposite end-portion of said tubular rod and extending at a right angle therefrom, a carrier-strap or handle secured at its ends to said loop-shaped devices, the enlargement or knobs of the said single end being adapted to enter said loop-shaped devices to be brought into separable retaining engagement with said 100 loop-shaped devices. 105

3. A combined stiffening and closing device for bags, comprising a pair of closing members for attachment thereto of the mouth-portions of the bag, one of said members comprising a single rod provided at its ends with enlargements or knobs, and the other member comprising a tubular rod, and a bar movably disposed within said tubular rod with an end of said bar project- 110 115 120 125 130

ing from one end of said tubular rod, a loop-shaped device rigidly connected with the projecting end of said bar and extending at a right angle therefrom, a second 5 loop-shaped device rigidly connected with the opposite end-portion of said tubular rod and extending at a right angle therefrom, a carrier-strap or handle secured at its ends to said loop-shaped devices, the enlargements or knobs of the said single end being 10 adapted to enter said loop-shaped devices to be brought into separable retaining engagement with said loop-shaped devices,

and a pull-spring within said tubular rod having one end secured within said rod and its other end attached to said movable bar for maintaining said retaining engagement of the said enlargements or knobs with the said loop-shaped devices.

In testimony that I claim the invention 20 set forth above I have hereunto set my hand this 5th day of March, 1918.

FREDERICK GOERTZ.
